UNITED STATES PATENT OFFICE.

CHRISTIAN AUGUSTUS ALBRECHT, OF BERLIN, GERMANY, ASSIGNOR TO MERGEN-
THALER LINOTYPE COMPANY, A CORPORATION OF NEW YORK.

TYPOGRAPHICAL MACHINE.

1,142,221.

Specification of Letters Patent.

Patented June 8, 1915.

Application filed April 11, 1914. Serial No. 831,112.

To all whom it may concern:

Be it known that I, CHRISTIAN AUGUSTUS ALBRECHT, a citizen of the United States of America, at present residing at Chaussee-
strasse 23, Berlin, N. 4, in the Empire of Germany, have invented new and useful Improvements in Typographical Machines; of which the following is a specification.

The magazines of a typographical composing and distributing machine of the type known under the trade mark "Linotype" occupy an oblique position in the machine, sloping downward and forward from their so-called magazine entrances through which the distributed matrices are returned into the magazines by the distributor, to their delivery mouths through which the matrices pass into the so-called assembler entrance. All the matrices of the same character are kept distinct from those of the other characters, by being one behind the other in their own channel; the obliquity of the magazines providing that they shall slide down their respective channels toward and through the delivery mouth by gravity. Consequently, the front matrix in any channel is always close up to the respective delivery mouth, the remainder standing in close order behind and touching the respective one in front. A larger quantity of some characters is necessary than of others. Consequently some channels are full while others may be only a third full.

There are two directions in which a magazine can be taken off the machine for another to be substituted for it—one is downward and forward and the other is rearward. In a forward substitution, the delivery mouths of both magazines concerned, are lower than their magazine entrances throughout it, so that there is no motion on the part of the matrices in the said magazines independent of the respective magazine. But a rearward substitution necessitates the magazine being tipped in such a way that its magazine entrance is for a time lower than its delivery mouth, the consequence being that all the matrices in a partly empty channel would then slide down the latter up to the usual magazine-entrance-closer and be damaged more or less by the sudden stoppage. The substituted magazine would be subjected to a like tipping, so that two fonts of matrices would be damaged at each substitution.

Throughout this specification and claims, the terms "matrix," "matrices" are to be read as including the respective alternatives "type die," "type dies."

The present invention consists in automatic means for locking the matrices in the partially full channels of a magazine being taken off its machine rearward, against sliding down their channels up to the magazine-entrance-closer and for unlocking the correspondingly circumstanced matrices in the substitute magazine as it is being substituted. These means are located partly in each magazine and partly on the frame of the machine.

The accompanying drawings illustrate a preferred constructional form of the application of the invention to a machine of the above mentioned type.

Figure 1 is a side elevation from the right hand of the machine; Fig. 2, a detail sectional side elevation through part of a matrix-channel; Figs. 3 and 4 are detail plans respectively of the unlocked and locked positions; and Fig. 5, a plan of a magazine in the respective position.

1 is a magazine having the usual matrices 2 in its matrix channels 3 and supported upon a so called magazine frame 4 pivoted by a transverse pivot 5 in or on the machine frame 6 so that it can be tipped for a substitution, the magazine being held on its frame 4 so that its channels 3 shall always register with the respective channels of the magazine entrance 7 and assembler entrance 8, by the engagement of a front-to-rear central bar 9 on its bottom face, in a corresponding groove 10 in the top of its frame 4, as heretofore.

11—Figs. 2 to 5 is a transverse bar having its top face flush with the top face of the magazine-bottom plate 12 and therefore blocking the channels 3 but for the channels 16 described farther on, its sides 13 engaged in corresponding grooves in the bar 9, one end 14 projecting beyond the respective side of the magazine 1 far enough to engage a cam face 15 on the machine frame 6 when the magazine is drawn rearward for a substitution and when so projecting from that side, holding channels 16 in the said top face of the bar 11, in register with the matrix channels 3 in the top face of the plate 12, and its opposite end 17 not projecting far enough beyond the respective

side of the magazine 1, to come into contact with the machine frame 6 as that magazine is being drawn rearward. This is the composing position and the matrices 2 slide down their channels in the usual way. As the said magazine is drawn rearward and before it and its frame 4 have been tipped downward beyond the horizontal, the end 14 engages the cam face 15 which forces the bar 11 across the magazine, thereby blocking the channels 3, and locking the matrices lying between it and the magazine delivery mouth closer and, further making its opposite end 17 project beyond the respective magazine-side as much as the end 14 had been projecting beyond its side. When the same magazine comes to be substituted, its bar-end 17 will engage with the cam face 18 on the respective side of the machine frame 6 and be pushed by it back again across the magazine, thereby unblocking the channels 3 by making the channels 16 register with them and consequently unlocking the matrices between it and the magazine entrance mouth closer.

A bar 11 is positioned in a magazine just to the rear of the columns of matrices which it is to lock and unlock. And as (as it has been pointed out) the columns vary in length, some being a third, others a half, and others say two thirds of the length of a channel 3, there may be a bar for each short length. Fig. 5 has assumed that there are two short lengths in the magazine.

In both cases, the matrices then between a bar 11 and the magazine delivery mouth closer are locked against sliding down the tipped magazine and injuring themselves when suddenly stopped by the magazine entrance closer.

Having described my invention I declare that what I claim and desire to secure by Letters Patent is:—

1. In a typographical machine, the combination of a magazine for the type or matrices removable from the machine at will, a laterally movable plate or bar located between the ends of the magazine for locking the type or matrices therein, and automatic means for moving said plate to active position as the magazine is removed from the machine.

2. In a typographical machine, the combination of a magazine for the type or matrices removable from the machine at will, a laterally movable plate or bar located between the ends of the magazine for locking the type or matrices therein, and automatic means for moving said plate to active and inactive position as the magazine is removed from and replaced in the machine, respectively.

3. Automatic means for respectively locking and unlocking the matrices in the partially full channels of the magazine of a

typographical composing machine consisting of one or more transverse bars slidable across the bottom plate of a magazine and channeled to register therewith and having always one end projecting to engage with a stationary cam face to slide the engaging bar far enough across the magazine plate to block its matrix channels as that magazine is being taken off the machine, and to project the other end far enough to engage with another stationary cam face as the same magazine is being substituted for a predecessor, to make the channels in the bar register again with the said matrix channels.

4. In a typographical machine, the combination of a supporting frame mounted to swing downwardly from its normal position in the machine, a magazine for the type or matrices arranged on the supporting frame and removable at will therefrom, locking means carried by the magazine for preventing the escape of the type or matrices therefrom, and automatic mechanism for rendering said locking means active during the removal of the magazine from its supporting frame.

5. In a typographical machine, the combination of a supporting frame mounted to swing downwardly from its normal position in the machine, a magazine for the type or matrices arranged on the supporting frame and removable at will therefrom, locking means carried by the magazine for preventing the escape of the type or matrices therefrom, and automatic mechanism for rendering said locking means active and inactive as the magazine is removed from and replaced on its supporting frame, respectively.

6. In a typographical machine, the combination of a supporting frame mounted to swing downwardly from its normal position in the machine, a magazine for the type or matrices arranged on the supporting frame and removable at will therefrom, locking means carried by the magazine substantially midway between its ends so as to engage within the partially filled channels and prevent the rearward shifting of the type or matrices therein, and automatic mechanism for rendering said means active during the removal of the magazine from its supporting frame.

7. In a typographical machine, the combination of a magazine formed with a series of grooves for the type or matrices and movable at will from its operative position, a movable plate or member formed with a corresponding series of grooves, and automatic means for moving said plate laterally as the magazine is moved from its operative position in order to shift the grooves in said parts out of registry.

8. In a typographical machine, the combination of a magazine formed with a se-

ries of grooves for the type or matrices, and movable at will from its operative position, a movable plate or member formed with a corresponding series of grooves, and automatic means for moving said plate laterally to shift its grooves into and out of registry with those in the magazine as the latter is moved to and from its operative position.

9. A magazine for typographical machines containing a plurality of columns of type or matrices of different lengths, and pro-

vided with a locking bar located between the ends of the magazine and adjusted to engage the upper matrices in the short columns and prevent the shifting of said columns in the 15 magazine.

In witness whereof I have hereunto set my hand in the presence of two witnesses.

CHRISTIAN AUGUSTUS ALBRECHT.
